UNITED STATES PATENT OFFICE.

JOHN F. O'CONNOR, OF CHICAGO, ILLINOIS, ASSIGNOR TO WILLIAM H. MINER, OF CHAZY, NEW YORK.

DETACHABLE DRAW-BAR AND YOKE CONNECTION.

1,220,537.

Specification of Letters Patent. Patented Mar. 27, 1917.

Application filed August 11, 1916. Serial No. 114,313.

To all whom it may concern:

Be it known that I, JOHN F. O'CONNOR, a citizen of the United States, residing at Chicago, in the county of Cook and State of Illinois, have invented a certain new and useful Improvement in Detachable Draw-Bar and Yoke Connections, of which the following is a full, clear, concise, and exact description, reference being had to the accompanying drawings, forming a part of this specification.

This invention relates to improvements in detachable draw bar and yoke connection.

The object of the invention is to provide a draw bar and yoke connection wherein the parts may be readily assembled or disassembled while the draft rigging is in position on the car.

In the drawing forming a part of this specification, Figure 1 is a side elevation of a portion of a draw bar and a yoke illustrating one embodiment of my invention. Fig. 2 is a horizontal sectional view of the structure illustrated in Fig. 1 and taken on the line 2—2 thereof. And Fig. 3 is a perspective view of the front portion of one of the yoke parts.

In said drawing, A denotes a draw bar or coupler, the butt of which is hollowed out and open to the rear, as clearly indicated in Fig. 2. The recess within the draw bar butt comprises a vertically extending front portion 10 substantially rectangular in cross section, a rear portion 11 of similar form

35 and a narrower connecting section 12, the latter being formed by oppositely disposed, vertically extending ribs or projections 13 formed on the inner face of the side walls of the draw bar butt. The yoke consists of two 40 similar parts B, B, each of which comprises an upper arm 14, lower arm 15, rear connecting piece 16 and front side plate 17 which connects the front ends of the upper and lower arms. The side plate 17 has its 45 inner face flush with the inner edges of the upper and lower arms 14 and 15, and on its outer face, the plate 17 is provided with a vertically extending channel or groove 18 which corresponds in size and shape to the

50 ribs 13. With the construction thus described, it is evident that the front portion of each yoke member B will fit against the side of the draw bar butt in the manner illustrated in Fig. 2 and the dimensions of 55 the parts are so arranged that, when the

yoke parts are in position, there will be a space 29 therebetween, which is slightly in excess of the depth of the channel or groove 18 in each of the yoke parts. This is done so that one yoke part may be first inserted 60 within the draw bar butt, after which the other yoke part may be similarly inserted and finally the two parts separated to the position shown in Fig. 2. In order to hold the parts in the separated position, I have 65 provided a vertical pin 19 which is insertible upwardly through the bottom wall of the draw bar butt and between the two yoke parts, as clearly indicated in Fig. 2. Each 70 of the yoke parts, on its inner face, is provided with a vertically extending groove 20 to fit the pin 19 and assist in properly positioning the latter. The pin 19 is preferably tapered at its top as indicated at 21 in Fig. 1, to thereby facilitate its insertion. 75 The lower wall of the draw bar butt is provided with a boss 22 through which is passed a cotter 23 to retain the pin 19 in position. As clearly indicated in Fig. 3 at 24—24, shoulders are provided at the forward ends 80 of the upper and lower yoke arms, which shoulders engage the rear vertical edges of the draw bar butt so that, in buffing, the blows are transmitted partly from the draw bar butt directly in line with the yoke arms 85 through said shoulders 24—24. In draft, it is apparent that the pull is exerted from the draw bar through the ribs 13 to the yoke parts.

With the construction shown, it is apparent 90 that the draw bar may be readily applied to or disconnected from the yoke while the latter is in position on the car, since the yoke parts may be moved together or separated while in operative position.

I claim:

1. In a draw bar and yoke connection, the combination with a draw bar having the butt thereof provided with a recess opened toward the rear, of a two-part yoke, the latter having its forward portions insertible within the recess and the draw bar butt, and means for retaining the yoke parts and draw bar in operative position when assembled.

2. In a device of the character described, 105 the combination with a draw bar having a recessed butt open to the rear, of a two-part yoke having its forward ends insertible within said recess, coöoperating, inter-engaging shoulders formed on the interior of the 110

draw bar butt and the yoke parts, and means for retaining the draw bar and yoke parts in operative position when assembled.

3. In a device of the character described, 5 the combination with a draw bar having a hollow butt, of a two-part yoke having the forward ends thereof insertible within said recess, and means for separating the yoke parts when the latter have their forward 10 ends assembled within the recessed butt.
4. In a device of the character described, 15 the combination with a draw bar, of a yoke formed in two parts, inter-engaging, co-operating shoulders formed on the draw bar butt and the yoke parts, and detachable means insertible between the yoke parts for forcing the latter into operative engagement with the draw bar and retaining the parts in proper assembled position.
5. In a device of the character described, 20 the combination with a draw bar having the butt thereof provided with a recess opened toward the rear, of a yoke consisting of two parts, each part having a plate at its forward end insertible within said recess, each 25 of said plates being grooved and the inner walls of the draw bar butt being shouldered

to fit into said grooves, and means for holding the yoke parts in spaced relation when inserted within the recessed butt.

6. In a device of the character described, 30 the combination with a draw bar having the butt thereof provided with a recess opened toward the rear, said recess having a restricted portion, of a yoke comprising two 35 similar parts, each of said parts having a vertically extending plate at its forward end, said plate portions of the yoke parts being insertible within said recess, the plates having a channel located to co-incide with the restricted portions of said recess, and a 40 vertically arranged key insertible through the bottom of the draw bar and between the yoke parts to separate the latter when mounted within the draw bar butt and to 45 hold the yoke parts and draw bar in operative engagement.

In witness that I claim the foregoing I have hereunto subscribed my name this 7th day of August, 1916.

JOHN F. O'CONNOR.
